DESIGN FOR A PLAYGROUND SLIDE OR SIMILAR ARTICLE

Carl H. Oermann, York, Pa.

Application September 22, 1941, Serial No. 103,443

Term of patent 7 years

To all whom it may concern:

Be it known that I, Carl H. Oermann, a citizen of the United States of America, residing at York, in the county of York and State of Pennsylvania, have invented a new, original, and ornamental Design for a Playground Slide or Similar Article, of which the following is a specification, reference being had to the accompanying drawing, forming part thereof, wherein the single figure is a perspective view of a playground slide or similar article embodying my new design.

The opposite side of the article is of substantially the same appearance as the side shown.

I claim:

The ornamental design for a playground slide or similar article, as shown and described.

CARL H. OERMANN.
